(57) **CLAIM**

The ornamental design for a princess raincoat, as shown and described.

DESCRIPTION

FIG. 1 is a perspective view of the princess raincoat.

FIG. 2 is a left side view of the princess raincoat.

FIG. 3 is a front view of the princess raincoat.

FIG. 4 is a top view of the princess raincoat.

FIG. 5 is a bottom view of the princess raincoat; and,
FIG. 6 is a back view of the princess raincoat.

The broken lines illustrated on the princess raincoat represent stitching.
